UNITED STATES PATENT OFFICE.

ADAM J. MAY, OF ROCHESTER, NEW YORK, ASSIGNOR, BY MESNE ASSIGNMENTS, TO RITTER DENTAL MANUFACTURING COMPANY, INC., OF ROCHESTER, NEW YORK, A CORPORATION OF DELAWARE.

HEADREST.

Original application filed May 18, 1923, Serial No. 639,884. Divided and this application filed May 28, 1924. Serial No. 716,507.

This invention relates to head rests of the variety adapted for use, for example, with a surgical or dental chair and, more particularly, to the pad means thereof for receiving 5 the patient's head, the chief object of the invention being to provide an improved pad construction of simple and efficient character, comprising but few parts affording a comfortable and effective support and capable 10 of being easily disassembled for the purpose of replacing the covering material or other parts.

To these and other ends the invention resides in certain improvements and combinations of parts, all as will be hereinafter more fully described, the novel features being pointed out in the claim at the end of the specification.

In the drawings:

20 Figure 1 is an elevation of a head rest fixture embodying the present invention;

Figure 2 is an enlarged central sectional view of one of the pads and its supporting means;

25 Figure 3 is a rear view of one of the pads detached and showing the outer covering partly broken away; and

Figure 4 is a front view of the body portion of the pad with the covering layers removed.

Similar reference numerals throughout the several views indicate the same parts.

The present invention comprises a head rest pad particularly suitable for use with a surgical or dental chair, having a supporting means or bracket adapted for attachment to the back of the chair with sectional parts adjustably connected with the bracket and with each other for adjustably supporting the pad 35 so that it may be easily located in the various different positions required in use. The supporting bracket is shown in Figure 1 as comprising a plate portion 5 adapted to be slidably supported in suitable vertical guideways 40 (not shown) on a chair or other article of furniture for elevational adjustment and to be clamped in position by any known and suitable means as well understood in the art. The plate carries an upwardly extending arm 50 6 with which is pivotally connected a sectional member 7, the upper end of which has pivotally connected therewith a curved arm 8. Adjustably connected with the upper end of

arm 8 as by means of links 9 is a yoke 10, the links being each pivotally connected at one end with the latter and at the other with arm 8 to form a parallel motion linkage clamped in adjusted position by a handle 11. The particular construction of these portions forms no part of the present invention being made 55 the subject matter of a copending application, Serial No. 639,884, filed May 18, 1923, for an invention in head rests, of which the present application is a division.

Pivots supported at its end on the spaced 60 ends of yoke 10 is an inner yoke 12 by which the pair of head pads 13 are carried in spaced relation as shown. The construction of both pads is the same so that a description of one is sufficient for both.

Each pad comprises, preferably, a supporting or backing body or plate, 14, of wood or other suitable material, in the present instance of circular or disk shape, although, of course, it may have an elliptical or other form of outline, as desired. Member 14 is preferably of increased thickness adjacent its periphery 15 so that the latter projects beyond the central portion on both sides, as shown in Figure 2. The periphery on the forward side is provided with a seat 16 on which is carried a raised annular marginal portion or ring 17 75 of soft resilient material such for example as sponge rubber, forming a yielding support for one or more sheets of flexible material 80 stretched taut over the forward side of the member as shown. In the present embodiment there is first applied an inner sheet 18 of leather, fabric or other suitable material stretched taut over the marginal portion 17 85 across the forward side of the pad with the peripheral portions of the sheet folded over on the rear side of the pad and there secured as by means of a plurality of securing devices or hooks 19 with which is engaged a draw cord 20 for stretching and holding the sheet which is thus supported at the front of the pad by the soft marginal portions 17 exclusively. In the present instance two such covering sheets are employed although one or a larger 90 number may be used. With two sheets, however, it has been found advantageous to slit the periphery of the inner sheet to form strips 21 to avoid overlapping folds and consequent unevenness in this under sheet. The outer sheet 22 is applied and stretched by similar 95 100 105

means, the folded portions of this sheet, however, being overlapped as shown and secured by similar hooks 23 and a cord 24. The use of two sheets increases the strength and resistance of the covering and the outer sheet may if desired have its outer surface ornamenteally finished in any suitable manner.

The pad body or backing 14 of each pad is supported by means of a stud or screw 25 threadedly engaged therewith in any suitable manner as by tapping into a metal hub 26. The other end of the screw is carried by an enlargement or mounting 27 formed at each end of the inner yoke 12. Mounting 27 is constructed with a forwardly projecting cylindrical flange 28 for engagement with the covering of the pad on the rear side thereof and the flange has a diameter sufficient for enclosing the securing hooks of the outer covering sheet as shown. When the pad body or backing is drawn home on its mounting by means of screw 25 flange 28 deflects the sheet portion at the rear side of the pad inwardly toward the recessed body 14, thereby increasing the tautness with which the sheets are preliminarily applied to any desired degree. This construction provides, between the covering material on the forward side of the pad and the recess or depressed intermediate portion of the body, a substantially air-tight chamber 28 in which the air is compressed by contact of an object with the pad to support the pad and increase the cushioning effect. By a substantially air-tight chamber is meant one which is not entirely free from leakage of air but which will permit gradual escape of a small amount of air therefrom when compressed by the weight of the object temporarily supported by the pad. The leakage under such conditions is preferably permitted to take place between certain comparatively close fitting parts of the pad as between the flexible covering and the back-

ing 14 and soft ring 17. The gradual leakage of the air from the chamber 28 permits the head of the user to readily adjust itself to the cushion by easing therein during the air escape period and during this time the soft ring 17 is slightly compressed by the inward pressure of the flexible covering due to the weight of the patient's head thereon. Upon removing the head, the depressed covering gradually assumes a normal position by reason of the refilling of the chamber 28 with air leaking into the same and by the expansion of the contracted ring 17 which is resilient to a considerable degree and more or less porous. The construction described affords a pad of a simple and economical form comprising but few parts combining softness and comfort for the head of the patient with the requisite strength and durability and the covering material may be quickly and conveniently removed and reassembled for cleaning or replacement as conditions may require. The pad construction as a whole is compact in form, with a simplicity of line affording a neat and attractive appearance.

I claim as my invention:

In a head rest, a pad backing having a raised margin on its forward and rear sides, a sheet of flexible material stretched taut over said margin on the forward side of the backing to provide a resilient supporting surface with portions of said sheet folded over on the rear side of said backing, securing means for drawing said folded over portions together adjacent the center of said backing rear, a mounting for said backing having a flange projecting against said folded over sheet portions and enclosing said securing means, and a support connecting the backing and mounting adapted for drawing said parts together and pressing said flange against the sheet folds to stretch said sheet.
